UNITED STATES PATENT OFFICE.

THOMAS WHEATLEY, OF SYRACUSE, NEW YORK.

MAILING-TUBE.

SPECIFICATION forming part of Letters Patent No. 696,614, dated April 1, 1902.

Application filed April 24, 1901. Serial No. 57,304. (No model.)

To all whom it may concern:

Be it known that I, THOMAS WHEATLEY, of Syracuse, in the county of Onondaga, in the State of New York, have invented new and 5 useful Improvements in Mailing-Tubes, of which the following, taken in connection with the accompanying drawings, is a full, clear, and exact description.

My invention relates to improvements in 10 mailing-tubes.

The object of this invention is to provide a light, stiff, and durable mailing-tube adapted to receive rolled articles—such as catalogues, drawings, and other matter—which it is desired 15 to protect from breakage or other injury in transportation and from which the inclosed matter may be readily removed without liability of injuring the same.

A further object of this invention is to provide 20 means upon said tube whereby the inclosed matter is held from endwise displacement.

To this end the invention consists in the combination, construction, and arrangement 25 of the parts of a mailing-tube, as hereinafter fully described, and pointed out in the claims.

Referring to the drawings, Figure 1 is a perspective view of a mailing-tube embodying my invention. Fig. 2 is a sectional view taken 30 on line 2—2, Fig. 1. Fig. 3 is a face view of the device seen in Fig. 1, showing the method of breaking the seal at the meeting edges of the transverse slit in the tube. Fig. 4 is a face view of a slightly-modified form of my invention. Fig. 5 is a sectional view taken on line 35 5—5, Fig. 4. Fig. 6 is a still further modified form of my invention.

Similar reference characters indicate corresponding parts in all the views.

It is well known that considerable difficulty 40 is experienced in removing the inclosed matter from stiff unyielding mailing-tubes, particularly when the tube contains a large amount of such matter, and also when the 45 cardboard or other heavy matter is rolled and placed in the tube. It is also known that it is difficult to retain the inclosed matter in position during transportation and that frequently such matter is lost by slipping 50 through the ends of the tube.

My invention is designed to overcome these difficulties; and it consists of a tube 1, open

at its opposite ends and provided with a lengthwise slit 2, preferably in a line substantially parallel with the axis of the tube. This 55 slit 2 is preferably covered by a suitable flap 3, which is usually of more flexible material than the tube and is usually adhesively secured thereto at opposite sides of the slit. This flap 3 forms a convenient seal for the 60 meeting edges of the tube and serves to hold said meeting edges in contact with each other during transportation, and although I have shown the flap 3 as consisting of a separate piece of paper or similar material it is evident 65 that the tube may be formed of a series of layers of paper or pasteboard and the outer layer formed of slightly-greater circumferential length than the remaining layers of the tube and extends beyond the meeting edges 70 or slit 2 for forming said flap. The inner face of the free edge of said flap may be provided with an adhesive substance or glue for permitting the same to be readily secured to the opposite wall of the slit of the tube. Inter- 75 posed between the flap and the adjacent portion of the tube, at one side of the lengthwise slit, is a flexible member 4, which is preferably arranged substantially parallel with the slit 2, extends beyond the opposite ends 80 of the tube, and is held in position by the flap 3 when the same is adhesively secured to the tube. This member 4 is preferably arranged in close proximity to the slit and serves as a 85 convenient means for breaking the seal, or rather for slitting the flap 3 from end to end when desired to remove the contents of the tube, it being understood that when said seal or flap is broken the tube may be readily expanded and the contents removed therefrom 90 without liability of tearing or otherwise injuring the same. As previously stated, the opposite ends of this member 4 extend beyond the corresponding ends of the tube, one end being usually of sufficient length to be returned 95 through the tube and secured by tying or by any other suitable means to the opposite end or extension of the member 4, preferably by tying, as seen in Fig. 2. By thus passing one end of the member 4 backwardly through the 100 tube and its contents and uniting the same to the opposite end of said member it is evident that the contents of the tube are firmly held from endwise displacement, thereby in-

suring the safe transmission of the matter contained therein.

When it is desired to remove the contents of the tube, it is simply necessary to untie the ends of the member 4, which may be a thread, a light wire, or other equivalent device, and to then draw one end toward the opposite end, thereby breaking the seal, or rather slitting the flap 3. Although I have shown in Figs.

- 10 1, 2, and 3 this member 4 as extended beyond the opposite ends of the tube, it is evident that one end only may be so extended for the purpose of returning the same through the tube and its contents, in which case I usually
- 15 provide the opposite end of the tube with a suitable fastening member, as a washer or disk 6, the central portion of which may be secured to the tube in any desired manner and the peripheral edge being free to spring 20 outwardly, and the cord or wire or equivalent member 4 may be inserted between the member 6 and the face of the tube, which serves to frictionally hold said end of the member 4 in position.
- 25 In Fig. 4 I have shown a tube 1 having a lengthwise slit 2 through one of its side walls extending inwardly from one end only a portion of the length of the tube and terminating at its inner end in a transverse slit extending only a small portion of its circumference for permitting the portion bounded by said slits to be sprung outwardly, thus permitting access to the inclosure for withdrawing the same.
- 30 35 At Fig. 6 I have shown a member 4 as consisting of a metal strip similarly inserted between the flap 3 and adjacent portion of the tube and having its opposite ends extended beyond the ends of the tube and adapted to be folded inwardly for retaining the contents of the tube from endwise displacement.
- 40 45 The operation of my invention is as follows: The tubes are first formed with a lengthwise slit, a thread, wire, or equivalent device is arranged in contact with the tube substantially parallel with and in proximity to the lengthwise slit, and a seal or paster is then adhesively applied to the tube to cover the slit and to hold the thread, wire, or equivalent device in position. The matter to be mailed or otherwise transported is then placed within the tube, one end of the thread, wire, or other device being returned through the tube and its contents and fastened at the opposite end of the tube for holding the contents of the tube from endwise displacement.
- 50 55 When desired to remove the contents of the tube, the ends of the device 4 are loosened and one end is drawn backwardly toward the opposite end of the tube, thereby breaking the seal or slitting the flap and revealing the slit in the tube, whereupon the tube may be readily expanded and the contents removed without liability of tearing or otherwise injuring the same.
- 60 65

Having thus described my invention, what I claim, and desire to secure by Letters Patent, is—

1. A mailing-tube partially divided or split lengthwise from one end for permitting said end to be expanded irrespective of the other end to facilitate removing of the contents of said tube, substantially as and for the purpose described. 70

2. A mailing-tube having one of its inclosing walls split from one end through only a portion of its length to facilitate removing of the contents of said tube, substantially as and for the purpose set forth. 75

3. A mailing-tube split from one end through only part of its length and having a transverse slit leading from the lengthwise slit to facilitate removing of the contents of said tube, substantially as and for the purpose described. 80

4. A mailing-tube having one of its inclosing walls split from one end through only a portion of its length and a flap covering the slit. 85

5. A mailing-tube slit lengthwise from one end through only part of its length, said slit terminating in a transverse slit of less length than the perimeter of the tube to facilitate removing of the contents of said tube, substantially as and for the purpose specified. 90

6. A mailing-tube having a lengthwise slit through only a portion of the length of one of its walls, and a fastening member adapted to be extended into the tube for holding the inclosed matter from endwise displacement. 100

7. A mailing-tube having a lengthwise slit through only a portion of the length of one of its walls, a flap secured to the tube and covering the slit and a flexible member between the tube and flap for slitting said flap. 105

8. A mailing-tube having a lengthwise slit through only a portion of the length of one of its walls, a flap secured to the tube and covering the slit and a flexible member between the tube and flap for slitting said flap, 110 said member being returned into the tube for holding the inclosed matter in position.

9. A mailing-tube slit lengthwise from one end, said slit terminating in a transverse slit of less length than the perimeter of the tube 115 and a flap secured to the tube and covering the lengthwise slit.

10. A mailing-tube slit lengthwise from one end, said slit terminating in a transverse slit of less length than the perimeter of the tube 120 tube, a flap secured to the tube and covering the lengthwise slit and a flexible member between the tube and flap for the purpose described.

In witness whereof I have hereunto set my hand this 19th day of April, 1901.

THOMAS WHEATLEY.
